No. 884,733.

PATENTED APR. 14, 1908.

J. HORSFIELD.
MOLD FOR CONCRETE WALLS.
APPLICATION FILED AUG. 22, 1907.

UNITED STATES PATENT OFFICE.

JOHN HORSFIELD, OF CHICAGO, ILLINOIS, ASSIGNOR OF ONE-HALF TO FRANK M. STRESENRENTER, OF CHICAGO, ILLINOIS.

MOLD FOR CONCRETE WALLS.

No. 884,733.

Specification of Letters Patent. Patented April 14, 1908.

Application filed August 22, 1907. Serial No. 389,647.

To all whom it may concern:

Be it known that I, JOHN HORSFIELD, a citizen of the United States of America, and a resident of Chicago, in the county of Cook and State of Illinois, have invented certain new and useful Improvements in Molds for Concrete Walls, of which the following is a specification.

This invention relates to an improvement 10 in the type of molds for concrete walls which constitute the subject matter of my former application for Letters Patent, Serial Number 381,407, filed June 29th, 1907; and has for its object to provide a simple and efficient structural formation and combination 15 of parts in the tie plates used to connect the mold planks together, and by means of which a symmetrical scoring of the surface of the wall is effectively and economically attained, 20 all as will hereinafter more fully appear.

In the accompanying drawings:—Figure 1, is a vertical section on line $x-x$ Fig. 2 of a pair of mold planks connected together by a tie plate of the present construction. Fig. 2, 25 is a sectional plan on line $x'-x'$ Fig. 1.

Similar numerals of reference indicate like parts in both views.

Referring to the drawings, 1 represents portions of a pair of mold planks arranged 30 one above the other to constitute a portion of a vertical side wall of the mold; and 2 the usual vertical studding by which the required support and rigidity is imparted to a mold wall formed of a series of super-imposed planks.

3 are the tie plates by which the mold planks 1 are secured in proper vertical alignment; such tie plates are formed of plate metal, so that when in place they will occupy but little vertical space between adjacent edges of the mold planks 1, and as usual 40 in the present type of wall molds. In the present invention, said plates are formed at their inner ends with right angle flanges 4 and 5 extending in opposite directions away from the main body of the plate and adapted to form stops for the adjacent inner corners of the mold planks to hold the same against inward lateral displacement. At their outer 45 ends, said plates are provided with extensions in which are formed a series of elongated slots 6 for the passage of the tapering keys or wedges 7, which are drawn into said slots and have bearing against the outer 50 faces of the mold planks 1, and are adapted

to force and clamp said mold planks against the flanges 4 and 5, as the keys or wedges are drawn into place.

The extensions of the plates 3 aforesaid may be integral portions of said plates, but 60 are preferably formed separate and riveted in place, as providing a more economical construction.

In the present improvement, the flanges 4 and 5 aforesaid are of an extended and convenient length, so as to meet corresponding constructions on the next adjacent tie plates to constitute a continuous projection within the mold cavity. Such flanges have some thickness and a suitable cross-section, such 70 as triangular as shown, and adapted to form horizontal grooves in the face of the wall, which can be converted into an ordinary "block face" by the use of a series of similar sections or strips 9 arranged in vertical spaced relation between pairs of the aforesaid horizontal flanges 4 and 5, and held in place by tongues or extensions 10 on the sections 9 engaging behind said flanges as shown in Fig. 1.

11 is a keeper piece of a hasp-like form, the central portion of which is adapted to straddle a studding 2, while the respective ends lie against the outer faces of the mold planks and are provided with orifices for the passage of the slotted extensions of the tie plate which receive the tapering keys or wedges 7 by which the parts are forced and held in proper position. Such construction is adapted to afford a very accurate and substantial connection for the planks comprising the molds for building walls and like finished structures.

Having thus fully described my said invention what I claim as new and desire to secure by Letters Patent, is:

1. A tie for mold planks comprising a main plate having right angle flanges at one end extending the width of the tie plate and adapted to form a continuous projection 100 within the mold cavity, and elongated slots at the other end, and tapering keys engaging said slots, substantially as set forth.

2. A tie for mold planks comprising a main plate having right angle flanges at one end extending the width of the tie plate and adapted to form a continuous projection within the mold cavity, and elongated slots at the other end, tapering keys engaging said slots, and a keeper piece having a hasp form 110

and provided with orifices for the passage of the outer ends of the main plate, substantially as set forth.

3. A tie for mold planks comprising a main plate having right angle flanges at one end extending the width of the tie plate and adapted to form a continuous projection within the mold cavity, and elongated slots at the other end, tapering keys engaging said

slots, and vertical strips having end extensions adapted for engagement behind said flanges, substantially as set forth. ¹⁰

Signed at Chicago, Illinois, this 19th day of August 1907.

JOHN HORSFIELD.
